M. L. URANN

PACKING BOX

Filed July 27, 1923

Inventor:

Marcus L. Urann

By Marcus L. Urann, Copeland & Kline
Attorneys.

UNITED STATES PATENT OFFICE.

MARCUS L. URANN, OF BRAINTREE, MASSACHUSETTS, ASSIGNEE TO THE UNITED CAPE COD CRANBERRY COMPANY, OF SOUTH HANSON, MASSACHUSETTS, A CORPORATION OF MAINE.

PACKING BOX.

Application filed July 27, 1923. Serial No. 654,165.

To all whom it may concern:

Be it known that I, MARCUS L. URANN, a citizen of the United States, residing at Braintree, in the county of Norfolk, State 5 of Massachusetts, have invented a certain new and useful Improvement in Packing Boxes, of which the following is a specification, reference being had therein to the accompanying drawings.

10 The invention relates to a new and useful improvement in packing boxes. It relates especially to boxes in which berries are packed and shipped to the market, and is more particularly intended for use in packing and shipping cranberries, although the invention is not limited to boxes for use with cranberries, but may be applied to boxes or shipping cases in which fruit or any other kind of article may be packed to which the 15 invention is adapted. Boxes for this purpose are usually made to contain a certain standard amount or quantity of the berries and is of rectangular form. The box is usually provided with a cover which is placed 20 on the box and fastened down after the box has been filled. If the box is larger than is required for the standard quantity of berries which are to be packed therein, so that the box is not quite full, the berries will rattle 25 around and the movement of the berries against each other will cause them to become bruised and make them damp, so that they will not keep well and the buyer will suspect slack pack. If, on the other hand, any 30 undue pressure is applied to crowd the berries down into the box, some of the berries will become crushed and they will spoil. With ordinary boxes, if the berries are hurriedly packed, as for instance, by just pouring them into the box, there is a tendency 35 for the berries in the corners to become loosely piled on top of each other with spaces which are bridged over by berries in the different layers, and when the box is 40 handled during the shipping and is shaken, these berries will settle down, leaving considerable loose space, so that the berries will rattle around. In order to overcome this, it has been common to carefully pack the 45 corners by hand so as to completely fill the corners and leave no unnecessary spaces. This takes considerable time and materially increases the expense of packing.

One object of the present invention is to

provide a cover for the box with a pressure member on the under side, so constructed that, when the cover is closed down, it will exert a pressure upon the berries in the corners, which is so distributed as to press both downward and toward the center of the box, thereby causing the berries which are in the corners to be compacted without bruising them before the cover of the box is nailed on. Another object of the invention is to make this pressure device in form of a cleat across 60 the ends of the cover to bind together and reinforce the several strips which make up the cover.

The invention will be fully understood from the following description when taken 70 in connection with the accompanying drawings, and the novel features thereof will be pointed out and clearly defined in the claims at the close of this specification.

In the drawings:

Fig. 1 is a perspective view showing particularly the under side of the cover for a box embodying the invention.

Fig. 2 is a longitudinal section of the box with the cover removed.

Fig. 3 is a longitudinal section of the box with the cover attached thereto, taken on the line 3—3 of Fig. 4.

Fig. 4 is a transverse section of the box on line 4—4 of Fig. 3.

Referring now to the drawings, 1 represents the bottom of the box, 2—2 the two end walls, and 3—3 the two side walls. The box is preferably of the standard half-barrel size, although the size is not material to the 90 invention. It is preferably also made of wood of any desired thickness and width of board, the preferred thickness for this size box being about one-half inch which will give the requisite strength, there usually being several widths of board for each side and end wall, both because the relatively narrow widths are cheaper and also more convenient for purposes of ventilation.

Preferably also transverse cleats 4 are 100 provided on the box bottom near the ends and also on the two box ends at the top and bottom, as shown in the drawings, for the purpose of strengthening or reinforcing the box.

The cover 5 is intended to be nailed on top of the box after the box has been filled. The cover is long enough to lap over the top

edges of the ends and sides of the box, as shown in the drawings. The cover is provided with two transverse cleats 6—6 attached to the under side of the cover far enough in from the ends so that, when the cover is set down onto the box, the outer edges 7 of the cleats will just fit inside of the ends 2—2 of the box. The cleat has a beveled under face 8, as shown in the drawings, the thick edge 7 being adjacent the end wall and the beveled face 8 facing downward and inward toward the interior and somewhat toward the middle of the box, so that when the cover is put upon the box, after it has been filled, the said cleat forms a sort of wedge which exerts a pressure upon the body of the berries lying along the ends and in the corners. This presses them not only downward but toward the interior of the box, in such manner as to overcome the lodging or bridging of the berries in the corners, in which are formed the unnecessarily large interstices. The thin edge 9 of the cleats is preferably not brought to a sharp edge. When the berries are first poured in, the pressure of the beveled face, being exerted in a direction at an angle to the ends and bottom of the box, not only is more effective in filling up the interstices, so far as the shape of the berries permits, but also is less liable to bruise the berries than if the pressure is exerted at right angles to the bottom or to the end walls.

While I have shown and described the presser members as cleats extending for the full width of the interior of the box, the essential part of said members is that portion which is effective at the corners of the box; therefore, instead of having the presser members extend the entire width of the box, the intermediate portion might be omitted,

leaving only those portions which are adjacent the corners. It is preferable, however, to have the presser member extend entirely across, as shown and described, so that it will perform the double function of serving as a pressure device and as a cleat to tie together the narrow strips which make up the cover as well as to reinforce the cover.

The box is preferably formed with ventilating slots 10 in its several walls, including the cover. In actual use, the box is usually turned upside down for shipment after the box has been filled and the cover fastened down, so that the member, which has been referred to as the cover, becomes in fact the bottom of the box, but as it has the function of a cover at the time of packing it is so designated in the specifications and claims.

What I claim is:

1. A packing box for berries having a cover provided with bevel faced members on its under side, which when the cover is closed fit in the corners of the box, the thicker edges of said presser members being adjacent the upright walls of the box so that the beveled faces exert a pressure on the berries in the box to press them downward and toward the middle of the box.

2. A rectangular packing box for berries having a cover adapted to close the top of the box, said cover having transverse bevel faced cleats adjacent its two ends, in such manner that when the cover is closed the thick edges of the cleats will be adjacent the inside of the end walls of the box and the beveled faces of the cleats will face inwardly and downwardly toward the interior of the box to press the berries toward the middle of the box.

In testimony whereof I affix my signature.
MARCUS L. URANN.
